UNITED STATES PATENT OFFICE.

BERT STUART, OF SEATTLE, WASHINGTON.

MATTRESS.

Application filed August 30, 1922. Serial No. 585,239.

To all whom it may concern:

Be it known that BERT STUART, a citizen of the United States, residing at Seattle, in the county of King and State of Washington, has invented certain new and useful Improvements in Mattresses, of which the following is a specification.

This invention relates to improvements in mattresses.

10 The primary object of the invention is to provide a mattress, provided with separate and distinct sections, whereby soiling, fouling, or disintegration of any one or more of the sections may be replaced without necessitating tearing down of the entire mattress structure.

A further object of the invention is to provide a mattress, wherein the surface will be substantially level as distinct from mattresses having undulations caused by tufts or buttons employed to hold the mattress together.

20 The invention also comprehends improvements in the details of construction and arrangement of parts, which will be herein-after described and particularly pointed out in the claims.

In the drawings:

Fig. 1 is a plan view with the cover removed.

Fig. 2 is a sectional view on line 2—2 of Fig. 1.

25 1 indicates the mattress as a whole, formed of canvas, ticking, or other suitable material, and which may be reinforced around its edges as at 2 by bars or otherwise covered as indicated at 3.

30 Extending from the sides and ends of the mattress structure are strips of canvas or other suitable material, indicated at 4 and 5. These strips are provided at intervals with slots 6 to interfit one with the other to form a series of compartments 7. The ends of the strips may be permanently attached to the frame or structure forming the body of the mattress.

35 In the compartments 7 stuffing is inserted, and over the top and bottom of the entire mattress structure is placed an upper and lower covering 8 and 9 to retain the stuffing in the compartments, and form uninterrupted surfaces throughout the area of the mattress.

In ordinary tufted mattresses, the stuffing is retained in place by the formation of tufts and cord, but experience has shown that in time the stuffing will shift despite the tufting and resultant construction, and cause an uneven surface to be produced, and when the mattress is to be renovated, the whole structure must be taken to pieces.

40 In the improved construction described, the separate compartments retain the stuffing and prevent same from moving from place to place, and at the same time the flexible strips lend sufficient resiliency to the structure. There is of course somewhat of a movement of the stuffing in the various compartments, but this movement is limited by the strips, so that none of the stuffing in any particular compartment will creep into an adjacent compartment.

45 While it is preferable to sew the edges of the strips 4 and 5 to the upper and lower covering and to the sides and ends of the mattress, yet this is not absolutely necessary because if the ends of the strips be sewed firmly to the side and end walls, the compartments will be sufficiently staple to withhold the resistance of the stuffing.

50 It is evident that if one of the compartments should become foul or disintegrated, it is only necessary to remove the upper covering and open up the particular compartment requiring repairs and restuff it without 55 in any wise disturbing any of the other compartments.

55 What I claim is:

A mattress, comprising bars forming the edges thereof, a covering for the bars, upper 60 and lower covering walls secured to the bar covering, a plurality of flexible strips secured at their ends to the bar covering, said strips having slits to interfit one with the other where the strips cross each other and 65 arranged to form a plurality of independent compartments, and a mattress filling arranged in each of said compartments, whereby the bars form a stiffened frame to carry 70 the strips, hold them in spaced relation, and substantially taut to prevent disarrangement thereof in the mattress and misplacement of the filling in the compartment.

75 In testimony whereof I affix my signature.

BERT STUART.
